UNITED STATES PATENT OFFICE.

CARRIE P. TRUESDELL, OF CLEVELAND, OHIO.

DESIGN FOR A SPOON.

SPECIFICATION forming part of Design No. 22,643, dated July 25, 1893.

Application filed May 4, 1893. Serial No. 473,047. Term of patent 7 years.

To all whom it may concern:

Be it known that I, CARRIE P. TRUESDELL, a citizen of the United States, residing at Cleveland, in the county of Cuyahoga and State of Ohio, have invented and produced a new and original Design for Spoons, of which the following is a specification, reference being had to the accompanying drawing, forming a part thereof.

10 In the drawing the upper surface or face of the spoon only is shown.

The leading features of my design consist of a Maltese cross at the top of the handle, having a passion cross in the center, within a ring; a shield below said Maltese cross; the shank, of essentially the form shown in the drawing, terminating in the bowl of the spoon, and an engraving in said bowl of the Epworth Memorial Methodist Episcopal Church, 20 Cleveland, Ohio. The Maltese cross A has the central ring B within which is the passion cross C. The lines A radiate from the periphery of the ring B to the outer edges of the cross A. At the junction of the arms which 25 form the cross C is a halo composed of radi-

ating lines. Depending from the lower arm of the cross A is the shield D. Below the shield D is the capital G of the semi-cylindrical, fluted shank H, consisting of a bud having three outer and two inner petals, as shown 30 in the drawing. The shank H is connected to the polyhedral, paneled base I by the part G' consisting of two series, one above the other, of petals; the lower of said series comprising three petals projecting slightly 35 beyond the upper series which has three outer and two inner petals.

The bowl F of the spoon is united at the top with the base I and has the church J engraved therein.

40 What I claim is—

The design for a spoon herein shown and described.

In testimony whereof I affix my signature in presence of two witnesses.

CARRIE P. TRUESDELL.
